RACK FOR FOOTBALL SHOULDER PADS OR THE LIKE

Toby Harper, Dolph, Ark.

Application May 26, 1958, Serial No. 51,087

Term of patent 7 years

(Cl. D80—9)

I claim:

The ornamental design for a rack for football shoulder pads or the like, as shown.
